GUARD FOR KNIFE SHARPENING STEELS

Filed Sept. 9, 1925

Inventor

PRESTON D. CALLUM,

By Lemmons & Lemmons

Attorney

UNITED STATES PATENT OFFICE.

PRESTON D. CALLUM, OF BALTIMORE, MARYLAND.

GUARD FOR KNIFE-SHARPENING STEELS.

Application filed September 9, 1925. Serial No. 55,210.

This invention relates to improvements in guards, and more particularly to guards for knife sharpening steels.

Heretofore, knife sharpening steels have not as a general rule been manufactured with a guard, and such steels as have been equipped with guards have been found totally deficient in so far as affording any protection to the user.

10 Sharpening steels such as are used by butchers, cooks, servitors and the like for the sharpening of butchering, carving, serving and other knives are generally defective in that they provide no safety means, thus 15 in the use thereof injury is often inflicted to the hand and particularly to the wrist and knuckles. Such injuries are occasioned by too long a stroke given to the knife undergoing sharpening, the slipping of the knife 20 from contact with the sharpening surface, or the holding hand grasping the handle of the sharpening steel too close to the sharpening area.

An object of my invention is to overcome 25 the existing defects in knife sharpening steels now in use by the production of a guard, which may be easily and quickly attached or removed and will, when attached or in use, efficiently perform all of its intended functions.

Another object of my invention is to provide a guard for a knife sharpening steel so constructed and attached, as to contribute a greater ease and comfort to the 35 user as well as safety and efficiency in operation.

A further object of my invention is to provide a guard for a knife sharpening steel so constructed and arranged as to receive 40 and deflect the blow of a knife in such a manner that no injury will be imparted to the blade, and that the blade will be prevented from leaving the guard.

A still further object of my invention is 45 to provide a guard for a knife sharpening steel which has the advantages of a positive guard, highly efficient in operation, and yet of such marked simplicity that its manufacture may be economically facilitated.

50 The marked advantage of this invention is the production of a guard for a knife sharpening steel susceptible of being applied to any sharpening steel now in use or any sharpening steel in the manufacture thereof, 55 the guard consisting primarily of a plate having a central aperture and a plurality

of lugs upon its edge, the lugs being radially disposed and equally spaced with respect to each other. The lugs are rolled or folded upon themselves and pressed upon the plate 60 in such a manner as to produce an abrupt parabolic curve on their inner faces which will have a tendency to deflect a knife blow and to catch the blade in a groove which is formed between the lug thus rolled or 65 folded and the face of the plate.

With these and other objects in view which may be incident to my improvements, the invention consists in the parts and combinations to be hereinafter set forth and 70 claimed, with the understanding that the several necessary elements comprising my invention, may be varied in construction, proportions and arrangement, without departing from the spirit and scope of the 75 appended claims.

In order to make my invention more clearly understood, I have shown in the accompanying drawings means for carrying the same into practical effect, without limiting 80 the improvements in their useful applications to the particular constructions, which for the purpose of explanation, have been made the subject of illustration.

In the drawings forming a part of this 85 specification:

Figure 1 is a side elevation of a knife sharpening steel with my improved guard attached.

Fig. 2 is a sectional view taken on line 90 2—2 Figure 1, looking in the direction of the arrows.

Fig. 3 is a sectional view taken on line 95 3—3 Figure 2 illustrating the folding or rolling of the lug upon itself and the top 95 or face of the plate, and

Fig. 4 is a plan view of a modified form of guard, the steel to which it is attached being shown in section.

Referring by numerals to the drawings 1 100 represents a handle, which may be of any desired shape or form according to the fancy of the producer. Mounted in the handle is a knife sharpening steel 2, the shank of which is passed through a ferrule 3. The 105 ferrule 3 is fitted snugly upon the handle and forms a collar around the steel. This construction is well known in implements of this character, the size and minor details varying according to their usage. The 110 implement here shown is a butcher's or meat cutter's steel.

In Figure 1, I have illustrated my improved guard as attached. The guard consists of a disk or plate 4 of soft brass, varying in size according to the use to which the 5 knife sharpener is to be put. This plate is formed of soft brass so as to absorb the blow with practically no injury to either the knife blade or the guard should the knife come directly in contact therewith, and at the 10 same time effectively guard the hand holding the sharpening steel and prevent injury thereto.

The plate 4 is provided with a central aperture 5 conforming to the size of the 15 steel upon which the plate is to be placed so as to produce a snug fit. The plate 4 is slipped over the steel 2 and secured to the ferrule 3 in any desirable manner. It may be formed as an integral part of the fer- 20 rule, riveted or sweated thereupon. The plate 4 is provided with a plurality of radially disposed lugs 6 equally spaced with respect to each other and to the central aperture. The lugs 6 are formed into stops 25 or buffers by folding or rolling the same inwardly upon themselves and pressing them tightly against the face of the plate in such a manner as to produce on their inner or oppositely disposed faces abrupt parabolic 30 curves 7. This curved surface has a tendency to deflect a knife blow. In folding or rolling and pressing the lug 6 upon the face of the plate, a V-shaped groove 8 is formed. This groove is designed to receive the edge 35 of a knife blade deflected from the sharpening steel and to contribute to the effectiveness of the stop in retarding or preventing a knife blade from passing off the hand guard after the guard has absorbed the 40 blow.

In Figure 4, I have shown a modification of the guard which consists in forming the plate 4 in the form of an octagon though it is to be understood that the same may be 45 formed of a polygon having any number of sides 9. The object is to prevent or retard a rolling motion of the implement when placed upon any surface, such as a work bench or work table. At each of the angles 50 formed on the edge by the particular configuration of the plate is a stop formed in the same manner as above described, the same being so shaped as to slightly bevel the angles, as indicated at 10 to avoid the 55 presence of sharp abrasive edges.

While I have shown and described the preferred embodiment of my invention, I wish it to be understood that I do not confine myself to the precise details of construction herein set forth, by way of illustration, as it is apparent that many changes and 60 variations may be made therein, by those skilled in the art, without departing from

the spirit of the invention, or exceeding the scope of the appended claims.

65

Having thus described the various features of my invention what I claim as new and desire to secure by Letters Patent is:

1. In a guard for a knife sharpening steel, a disk and a plurality of members projecting from the plane of the disk.

2. In a guard for a knife sharpening steel, a disk and a plurality of members on the edge of the disk projecting at an angle from the plane of the disk.

3. In a guard for a knife sharpening steel, a disk, and a plurality of members on the disk projecting at an acute angle from the plane of the disk.

4. In a guard for a knife sharpening steel, a disk and a plurality of members projecting at an angle from the edge of the disk.

5. In a guard for a knife sharpening steel, a substantially circular plate and a plurality of members projecting from the plane of the plate.

6. In a guard for a knife sharpening steel, a substantially circular plate having an aperture in the center thereof and a series of lugs projecting at an angle from the edge of the plate.

7. In a guard for a knife sharpening steel, a disk having an aperture in the center thereof and a plurality of bent lugs on the periphery of the disk.

8. In a guard for a knife sharpening steel, a disk having an aperture in the center thereof, and a plurality of bent lugs upon the disk in spaced relation to each other.

9. In a guard for a knife sharpening steel, a disk having an aperture in the center thereof, and a plurality of bent lugs upon the periphery of the disk in spaced relation to each other and to the aperture.

10. In a guard for a knife sharpening steel, a plate having an aperture in the center thereof, a plurality of lugs upon the periphery of the plate and the lugs turned upon the face of the plate.

11. In a guard for a knife sharpening steel, a plate having an aperture in the center thereof, a plurality of radially disposed and equally spaced lugs upon the edge of the plate, the lugs turned upon the face of the plate and grooves between the lugs and the face of the plate.

12. In a guard for a knife sharpening steel, a plate having an aperture in the center thereof, a plurality of radially disposed and equally spaced lugs upon the edge of the plate, the lugs rolled upon the face of the plate, abrupt parabolic curves upon the inner faces of the lugs and slots between the lugs and the face of the plate.

In testimony whereof I affix my signature.
PRESTON D. CALLUM.
